UNITED STATES PATENT OFFICE.

COLIN R. WALCOTT AND WALTER J. PIKE, OF NEWAYGO, MICHIGAN, ASSIGNORS TO
MILLARD F. HATCH, OF NEWAYGO, MICHIGAN.

VIBRATILE SCREEN.

Application filed August 31, 1922. Serial No. 585,349.

To all whom it may concern:

Be it known that we, COLIN R. WALCOTT and WALTER J. PIKE, citizens of the United States, residing at Newaygo, in the county of 5 Newaygo and State of Michigan, have invented new and useful Improvements in Vibratile Screens, of which the following is a specification.

The present invention relates to vibratile screens; and its object is, generally, to provide improved means for supporting such screens; and, more particularly, to provide means for yieldingly supporting the middle portion of the screen independently of, 10 and movably relatively to, the means which supports its edges; and further, to provide improved means for stretchingly mounting such screens; and further, to provide improved means for preventing leakage at the 15 edges of such screens; and further, to provide improved means for preventing the breaking of such screens adjacent the mounting thereof.

These and any other objects hereinafter appearing are attained by, and the invention finds preferable embodiment in, the structure hereinafter particularly described in the body of this specification and illustrated by the accompanying drawings, in which:—

30 Figure 1 is a front view of a vibratile screen structure;

Figure 2 is a sectional view thereof taken on a vertical plane corresponding to line 2—2 of Figure 1;

35 Figure 3 is a like view (enlarged) of certain parts;

Figure 4 is a transverse sectional view of a portion thereof taken on line 4—4 of Figure 3;

40 Figure 5 is a side view of a portion thereof;

Figure 6 is a plan view of a rotatable shaft and cam wheel carried thereby;

45 Figure 7 is a transverse sectional view (enlarged, of certain parts taken on line 7—7 of Figure 1;

Figure 8 is a side view of the same;

50 Figure 9 is a transverse sectional view (enlarged) of a portion of said structure taken on line 9—9 of Figure 1; and

Figure 10 is a transverse sectional view of certain parts taken on line 10—10 of Figures 1 and 3.

55 In the embodiment of the invention chosen for illustration by the drawings and for

detailed description in the body of this specification, the frame 1 of the structure, pivotally mounted at 2 on a suitable base 3, may be swung to a desired inclined position—say at an angle of 45 degrees—and sustained in such position by the arm 4 in which is threaded a screw 5 for effecting such angular adjustment. The material to be screened may be delivered to the upper side of the screen 6 through the inlet 7, the portion of 60 such material which passes through the screen falling on the inclined bottom 8 of the frame and thence passing through the vent 9. The screen is supported adjacent its opposite side edges on the frame in the following manner: As particularly shown in Figures 1, 7 and 8, one (or preferably both as shown) of these side edges are secured to strips 10 bent over to form hooks 11 (see Figure 7), said strips resting on the inwardly-extending shelf portion 12 of the frame. A member 13 abuts at its upper or outer edge portion 14 on the inner surface of the body portion 15 of the frame, (its said portions 12 and 15 being thus angularly disposed relatively to each other), and the lower or inner edge portion 16 of the member 13 engages in the hook of strip 10, all as seen in Figure 7. Screws 17 threaded in the frame and passing through the member 13 serve to 65 stretch the screen to a desired tautness, the lower edge portion 16 of the member 13 sliding along the shelf portion 12 of the frame toward the frame's other portion 15, and the upper edge portion 14 of said member sliding along the inner surface of the portion 15 of the frame and away from its shelf portion 12, as the screw 17 is screwed down. The screen is yieldingly held in the degree of tautness to which it has been thus 70 adjusted by the spring 18 surrounding the shank of the screw and pressing between its head and the washer 19 which rests on the surface of the member 13. To prevent leakage of the material being screened, packing strips, 49, 20, of suitable material, as felt, are 75 respectively positioned between the upper edge portion 14 of the member 13 and the frame's portion 15 and between the screen or its edge strip 10 and the frame's shelf portion 12. These packing strips being resilient, and the lower fold of the screen's edge strip 10 being bent downwardly at 21, the screen adjacent its supported edges is prevented from a sharply bending movement 80

along its lines of support so that the repeated vibrations of the screen may not result in a breaking thereof adjacent such edges.

The screen is vibrated in a direction perpendicular to its sides by suitable means, as by the cam wheel 22 on the shaft 23 turning in bearings 24 on the cover 25 hinged at 26, said shaft being rotated as by the pulley 27. The movement of this cam wheel 10 gradually depresses the anvil 28 mounted on the free end of the springable bar 29, which action depresses the screen by pressing the bar 29 against the outer end of the upwardly or outwardly extending post 30 15 secured to the middle portion of the screen. This post is thus secured as by screws passing through the thin bars 31, 32 on the opposite sides of the screen, the upper bar 31 being attached at its ends to the frame as by lugs or bolts 33 passing through elongated slots 34 in said bar, whereby a sidewise adjustment of the screen on the frame is permitted.

The middle portion of the screen is supported by the following mechanism:

A plunger 35, slideable in a bearing 36 on the frame, has a head 37 adapted to contact the lower side of the screen, being pressed into such contact by a spring 38, as 50 particularly shown in Figures 2 and 3. The tension of this spring is regulated by a second plunger 39 slideable in the plunger 35 as shown in Figure 3 and adjustable by a nut 40 on the screw 41 carried at the free end of the lever 42 fulcrumed at 43 on the frame and supporting the lower end of the second plunger 39, as will be readily understood. It will be seen that the middle portion of the screen is thus supported independently of its edge portions and by means 55 movable relatively to the means supporting such edge portions; and that as the high parts of the cam wheel pass off of the anvil 28, the middle portion of the screen is suddenly thrown upwardly by the spring 38. A flexible cover 45 of suitable material (as

leather) and attached to the under side of the bar 29 and to the upper side of the cover 25 prevents leakage through the opening 46 in the cover.

50

The invention being intended to be pointed out in the claims, is not to be limited to or by details of construction of the particular embodiment thereof illustrated by the drawings or hereinbefore shown or described.

55

What is claimed is:

1. In mechanism of the character described; a screen; a frame having angularly-disposed portions; means for mounting the screen on the frame comprising, a member having an edge portion abutting one portion of the frame and another edge portion holdingly engaging the screen therebetween and the other portion of the frame, and adjustable means for moving and holding said member on the frame; packing intermediate said member and the first-mentioned portion of the frame, and intermediate the screen and the last-mentioned portion of the frame.

60

2. In mechanism of the character described; a screen; a frame having angularly-disposed portions; means for mounting the screen on the frame comprising, a member having an edge portion abutting one portion of the frame and another edge portion holdingly engaging the screen therebetween and the other portion of the frame, and adjustable means for moving and holding said member on the frame; a resilient strip intermediate the screen and the last-mentioned portion of the frame.

65

In testimony whereof we have hereunto set our hands at Newaygo, Michigan, this 23rd day of August, 1922.
